UNITED STATES PATENT OFFICE.

MARY JANE WEAVER, OF CINCINNATI, OHIO.

DISH-WASHING MACHINE.

1,106,430.

Specification of Letters Patent. Patented Aug. 11, 1914.

Application filed March 5, 1914. Serial No. 822,689.

To all whom it may concern:

Be it known that I, MARY JANE WEAVER, a citizen of the United States, residing at Cincinnati, in the county of Hamilton and State of Ohio, have invented certain new and useful Improvements in Dish-Washing Machines, of which the following is a specification.

This invention relates to certain improvements in dish washers and the like; and the objects and nature of the invention will be readily understood by those skilled in the art in the light of the following explanation of the accompanying drawings illustrating what I now believe to be the preferred embodiment from among other formations, arrangements and constructions within the spirit and scope of the invention.

An object of the invention is to provide certain improvements in combinations of parts and in the construction and arrangement of elements whereby a highly efficient durable and comparatively simple dish washer will be produced.

The invention consists in certain novel features in construction and in combinations and arrangements as more fully and particularly set forth and specified hereinafter.

Referring to the accompanying drawings, Figure 1, is a perspective of the washer complete. Fig. 2, is a vertical longitudinal section thereof. Fig. 3, is a horizontal section. Figs. 4, and 5, are detail views.

In the particular example illustrated, I employ a tub, tank or receptacle 1, having its vertical or surrounding wall depending a distance below the horizontal plane of the tank bottom to form the depending bottom supporting flange 2. The vertical surrounding wall of the tank is formed with an outward longitudinal bulge or offset 3, extending throughout the length of the tank and forming a vertical chamber or recess with in the tank extending from the bottom of the tank to the top thereof and at its inner side open into the interior of the tank. This chamber or recess is permanently closed at the top of the tank by fixed top wall 4, extending to and terminating at the open top of the tank. The open top of the tank is normally closed by the removable cover 5, formed to snugly fit down within the vertical wall of the tank and at the inner edge of the wall 4.

Within the vertical side recess or enlargement formed by the bulge 3, I arrange the vertical barrel 6, of a reciprocating pump. This barrel is formed with any suitable foot or base 7, resting on the tank bottom. The barrel is removably secured in the recess and against the vertical wall thereof by any suitable means, such as U-shaped clips 8, partially embracing the barrel and having their flanged ends clamped to the tank wall by stove bolts 9, extending through the wall and said ends, or by any other suitable means. The pump barrel contains any suitable piston 10, provided with a piston rod 11, extending upwardly through and slideable in a suitable guide bearing 12, in the top wall 4. The exposed handle or upper end of the piston rod is preferably provided with any suitable handle such as 13. A coiled cushioning spring 14, is preferably arranged on the piston rod to cushion the upward stroke of the piston by being compressed between the piston and under side of wall 4, as the piston reaches its limit of upward movement.

At its lower end, the pump barrel is provided with inlet opening 15, arranged but a short distance above the tank bottom and this opening is controlled by pump or check valve 16, to permit inflow of liquid from the tank bottom and into the pump barrel when the piston is drawn up but to prevent outflow from the barrel through said opening when the piston is forced down. The lower end of the pump barrel, above said suction inlet, is provided with a laterally projecting discharge chamber 17, into which the pump barrel discharges through a suitable opening controlled by check valve 18, arranged to close said opening under pump suction and to permit discharge from the barrel and into the chamber under outward or pump pressure when the piston is forced down to close the pump valve and to force the liquid from the pump barrel. This valve 18, is provided to prevent the pump drawing liquid from the discharge chamber 17, when the pump piston is moved up on its suction stroke.

The discharge chamber is provided with two outlets, one opening horizontally through the side or inner end of the chamber into a horizontal inwardly projecting nipple 20, rigid with the chamber, and detachably receiving a horizontal pipe 21, dis-

charging into and usually rigid with an upwardly discharging spray or rose head 22, arranged approximately centrally of the lower end or bottom of the tank. The other outlet from said chamber is through vertical fixed pipe 23, opening into the top of the chamber and extending upwardly therefrom beside the pump barrel and at its upper end removably receiving goose neck 5 pipe section 25, at its inner end provided with the downwardly discharging spray or rose head 26, arranged approximately centrally in the upper end of the tank immediately under the tank cover.

10 15. The goose neck 25, has an approximately straight free end that slips removably and vertically onto the upper end of the fixed vertical discharge pipe, forming a slip joint therewith, while the opposite end of the 20 goose neck is fixed to the downwardly discharging spray head 26. The goose neck carrying its spray head can be easily slipped onto and from said fixed pipe and can be swung horizontally on said fixed pipe as a 25 center to bring the spray head against the wall of the tank and thereby leave the center of the tank unobstructed and thereby allow free access to the interior of the tank 30 after the dish rack, hereinafter described, has been located in the tank.

The pipe length 21, carrying its spray head 22, is readily removable from and applicable to the nipple 20, as it slips thereon and therefrom. The head 22, is preferably 35 provided with a foot or base 27, fixed thereto and depending therefrom and removably resting on the tank bottom to support said head and its pipe and maintain the head in the desired horizontal position. If so desired, the pipe 21, can be locked against accidental detachment from the nipple 20, by a 40 readily-accessible removable pin 28, passed down through the pipe and nipple.

Suitable means are provided to support 45 the dishes or other articles to be washed, within range of the spray discharged by the said two discharge heads. For instance, I show an open-work or wire rack or carrier 50 removably arranged within the tank and resting on the floor thereof and adapted to carry rows of plates or the like and expose them to the action of the sprays. This rack is arranged vertically and about centrally in the tank below the upper spray head and 55 rises from the floor around the lower spray head. The rack is made up of pairs of spaced vertically disposed or looped rods or wires forming a number of upwardly converging holders 29, each arranged to hold 60 a vertical row of overlapping plates on edge at the exterior of the rack with each plate arranged outwardly beyond or spaced from the next plate above. The upper ends of these holders are secured together by united 65 cross connections 30, while the lower ends of

the racks form supporting legs 31. The lower portions of the racks are held spread and are secured together by a loop or ring 32, to which the racks are secured.

The center of the rack is open and the lower sprayer head is arranged below this open center with the plates forming an approximately conical pile extending upwardly around said open center so that the descending spray from the upper head will sweep said dishes, particularly the outer surfaces thereof, while the upwardly directed spray from the lower head will also sweep said dishes, particularly the inner surfaces thereof.

70 The cross portions 30, of the longitudinal or upwardly extending wires of the tray form handle portions at the upper end of the tray whereby the same with its load can be readily lifted into and from the tank 75 when the upper spray head and its goose neck has been removed. The depending supporting legs 31, formed by the lower ends of the longitudinal holder-forming wires, rest on the bottom of the tank and hold the 80 dishes above the water filling the lower portion of the tank below the lower spray head. If so desired, a wire or other open work basket 39, can be provided to receive silver 85 ware and this basket is provided at its upper 90 end with supporting hooks 40, by which the basket can be removably attached to suitable portions of the wire rack so that the basket will hang in the open space within the rack and the articles in the basket will 95 be subject to the cleansing action of the spray from the heads.

100 In use, the tank is supplied with hot water to a level above the pump suction inlet but below the perforated top face of the lower spray head, and the pump is then operated to effectively spray the dishes previously arranged in the rack as before described. After the dishes have drained and dried, 105 they can be removed from the tank separately without disturbing the rack and without removing the upper spray head, or the upper spray head and its goose neck can be removed and the rack with the dishes 110 therein can be lifted from the tank. I provide a water outlet through the bottom of the tank through which the water can be drained from the tank whenever desired. In the example illustrated, this water outlet or discharge 41, is located in the bottom of the tank at the lower end of the recess formed by the bulge in the tank wall and hence is directly below the permanent top wall of said recess. The outlet is normally tightly closed or plugged by a tapered plug or valve 42, provided with a valve stem or lift rod 43, extending through and slidably in an opening in said permanent top wall and provided with an exposed knob or handle above said wall.

The lower end of the stem 43, is guided by a bracket 44, fixed in the tank and the valve is yieldingly held in, and is returned after opening to, closing position by a coiled or 5 volute spring 45, compressed between the plug and said bracket. The washer is preferably carried and held elevated by a detachable portable folding stand 46, provided with casters to render the stand and 10 the washers thereon readily portable or movable along the floor or elsewhere.

It is evident that various changes, modifications and variations might be resorted to without departing from the spirit and 15 scope of my invention and hence I do not wish to limit my invention to the exact disclosures hereof.

What I claim is;—

1. A washing machine comprising an 20 open-top tank, a removable cover for closing said open top, said tank provided approximately throughout its vertical length with a recess in its surrounding wall formed by an outward bulge in said wall, said recess having 25 a permanent top wall, a pump barrel arranged in said recess, means removably clamping said barrel to the bulged portion of the wall, said barrel having a foot engaging the tank bottom and a suction inlet 30 near said bottom, said pump provided with operating means extending to the exterior of the tank through said wall, discharge pipes within the tank extending from said barrel to the upper and lower portions of the interior 35 of the tank and there provided with spray heads, said pipes having removable sections carrying said spray heads and located below and independent of said cover, and removable means in said tank to receive 40 and carry the dishes, substantially as described.

2. A washing machine comprising a tank having an open top and a cover therefor, a pump secured within the tank and having actuating means operative from the exterior 45 thereof, said pump comprising a barrel having a valved inlet from the bottom of the tank and also having a discharge chamber with a discharge outlet from the barrel thereinto provided with a valve to prevent 50 back flow of water from the chamber into the barrel, a pipe in the lower portion of the tank extending from said chamber and provided with an upwardly discharging spray head, and a pipe extending from said 55 chamber to a point below and independently of said cover and provided with a downwardly discharging spray head.

3. A washing machine comprising a tank having a removable cover, a removable dish 60 rack in said tank, a pump having a suction inlet from the bottom of the tank and also having a fixed discharge chamber into which the pump discharges, means to prevent liquid from flowing back from said chamber 65 into the pump, a discharge pipe from said chamber comprising a removable section in the bottom of the tank having a foot and an upwardly discharging spray head, and another discharge pipe from said chamber 70 arranged within the tank below and independent of said cover and above said dish rack and comprising a removable goose neck provided with a downwardly discharging spray head. 75

In testimony whereof I affix my signature in presence of two witnesses.

MARY JANE WEAVER.
